DESIGN FOR A TRUCK TANK

Otto N. Gredell, Kansas City, Mo., assignor to Standard Steel Works, North Kansas City, Mo., a corporation of Missouri

Application July 6, 1936, Serial No. 63,602

Term of patent 7 years

To all whom it may concern:

Be it known that I, Otto N. Gredell, a citizen of the United States, residing at Kansas City, in the county of Jackson and State of Missouri, have invented a new, original, and ornamental Design for Truck Tanks, of which the following is a specification, reference being had to the accompanying drawing, forming part thereof.

Fig. 1 is a plan view of a truck tank showing my new design.

Fig. 2 is a side elevational view of the truck tank.

Fig. 3 is a perspective view of the truck tank.

Fig. 4 is a rear elevational view of the truck tank.

The characteristic feature of the design resides in the rear portion of the truck tank.

I claim:

The ornamental design for a truck tank, as shown and described.

OTTO N. GREDELL.
